UNITED STATES PATENT OFFICE.

JOHN E. CONZELMAN, OF ST. LOUIS, MISSOURI, ASSIGNOR TO UNIT CONSTRUCTION COMPANY, OF ST. LOUIS, MISSOURI, A CORPORATION OF DELAWARE.

CONCRETE CONSTRUCTION.

1,031,047.

Specification of Letters Patent. Patented July 2, 1912.

Original application filed April 14, 1910, Serial No. 555,354. Divided and this application filed June 5, 1911. Serial No. 631,280.

To all whom it may concern:

Be it known that I, JOHN E. CONZELMAN, a citizen of the United States, residing at the city of St. Louis, State of Missouri, have invented certain new and useful Improvements in Concrete Construction, (Divisional Case Q,) of which the following is a specification.

This application is a division and continuation of one filed by me April 14, 1910, Serial No. 555,354.

This invention relates to certain new and useful improvements in concrete construction, in which concrete girders are used to support concrete slabs and are themselves supported by means of columns or uprights.

The object of the invention is to provide a rigid and unitary structure in which the girders and slabs are effectively connected to each other and to the supporting column or upright and in which wide girders, channeled to give a paneled effect, may be utilized.

In the drawings: Figure 1 is a fragmentary perspective view of the present invention; Fig. 2 is a top plan view, and Fig. 3 is a section on the line 3-3 of Fig. 2.

Each girder 1 is preferably formed with a rectangular configuration, and is comparatively wide and thin. Each longitudinal edge of the girder 1 is provided with a shoulder 2 on which the slabs 3 seat. The girder ends rest upon a cap 4, the latter resting on the top face 5 of cap 6, cap 6 being carried by the supporting column 7. A stud 8 is carried by cap 6, and extends into an opening 9 in cap 4 so that a space 10 above the stud is left within opening 9. Each corner of girder 1 is preferably beveled so that, when the ends of the girders are placed upon cap 4, each beveled corner fits against a similarly beveled corner of an adjoining girder. When the girders 1 are placed upon cap 4 in the manner just described, a space 11 located above the cap is provided, the space 11 being disposed above the space 10.

For the purpose of providing a girder having a section of maximum economy, *i. e.*, a girder containing no excess of concrete, the middle portion of the under side of the girder is channeled between approximately the quarter points of the span thereof so that each side of said girder is provided

with a flange or rib 12. As additional strengthening means, reinforcing bars 13 are embedded near the top surfaces of girders 1 and are spaced at intervals in same. The bars 13 extend transversely of the girders, and are bent downwardly at their ends to form stirrups 14 adjacent the girder sides, the purpose of the bars 13 being to stiffen the girders, to prevent transverse bending of the girders, should an excess load be placed on either side of the same. Bars 15 also extend transversely of girders 1 and are spaced at intervals in the girders at points near the bottom surfaces thereof, in order to carry the load between flanges 12. Short bars 17 also underlie bars 13 and project from the girder ends, the bars 17 being arranged to assist in taking up the tensile stress obviously existing in the top surface of that part of the girders 1, that rest upon cap 4. Bars 18 lie near the bottoms of flanges 12 and extend through the stirrups 14. Some of the bars 18 are bent upwardly, and extend near the girders and project from the ends of the latter. The bars 16, 17, and 18 that project from the girder ends extend into space 11 and preferably overlap similar bars 16, 17, and 18 respectively, projecting from the adjacent end of an oppositely-disposed girder.

Each slab 3 is preferably reinforced in both directions by means of bars 21 in order to distribute its load to the girders supporting the same, the bars 21 being embedded near the bottom faces of slabs 3.

As will be seen from Figs. 1 and 3, the top faces of slabs 3 extend above the top faces of the girders, thereby providing a space of cruciform between the inner side faces of the four girders, as illustrated in Fig. 2. The bars 21 in the slabs 1 project from the sides of the slabs and overlap the ends of similar bars 21, which project from the sides of an adjacent slab. The cruciform space is filled with grout or plastic concrete 40 which runs into and fills spaces 10 and 11. The grout is leveled off flush with the top faces of slabs 3, and, when it sets, unites the slabs 3, girders 1, cap 4, and column 7 integrally together.

By reason of forming wide girders 1, the space 11 is consequently comparatively large, thereby allowing the base of a superimposed column, not shown, to be set in

said space without the necessity of providing the girder ends with cutaway portions, as has been customary heretofore, the bars 16, 17, and 18, being spaced so that an open space between the innermost bars is left in the center of space 11 for the placing of the base of the column, not shown, therein.

What is claimed is:

In concrete construction, a column, a stud 10 carried by the upper end of the column, a cap seating on said upper end of the column and having an opening in which the stud projects, the stud terminating below the top face of the cap to form a concrete receiving 15 chamber, two pairs of oppositely disposed girders having their ends seating on the cap and their corners in abutting engagement to form a second concrete receiving chamber that surrounds and is located above 20 said first named concrete receiving chamber, rods carried by each girder and project-

ing horizontally into said second named concrete receiving chamber, shoulders on the sides of each girder below the tops thereof, slabs seating on the shoulders and 25 having their top faces extending above the girder tops, reinforcing bars carried by the slabs and projecting beyond the sides and ends thereof and overlying the girder tops, the bars of opposing slabs overlapping one 30 another, and a concrete filler seating on the girder tops and disposed flush with the slab tops and extending down to completely fill both of said pockets, whereby the filler connects the slabs to the girders, the girders 35 to the cap, and the cap to the column.

In testimony whereof I hereunto affix my signature in the presence of two witnesses.

JOHN E. CONZELMAN.
